A. I. RISSE

LIQUID LEVEL ADJUSTER FOR BOTTLE FILLING MACHINES

Original Filed Oct. 15, 1923

Inventor:
Arthur I. Risser,
By Sheever & Cox Atty.

UNITED STATES PATENT OFFICE.

ARTHUR I. RISSE, OF CHICAGO, ILLINOIS, ASSIGNOR TO U. S. BOTTLE MACHINERY CO., OF CHICAGO, ILLINOIS, A CORPORATION OF ILLINOIS.

LIQUID-LEVEL ADJUSTER FOR BOTTLE-FILLING MACHINES.

Original application filed October 15, 1923, Serial No. 668,457. Divided and this application filed April 16, 1924. Serial No. 706,862.

To all whom it may concern:

Be it known that I, ARTHUR I. RISSE, a citizen of the United States, residing at Chicago, in the county of Cook and State of Illinois, have invented a certain new and useful Improvement in Liquid-Level Adjusters for Bottle-Filling Machines, of which the following is a specification.

This is a division of my earlier application for bottle filling machine, Serial Number 668,457, filed October 15, 1923.

While the mechanism of this invention is applicable to adjusting the level of liquid in various mechanisms, it is of especial value in automatic machines for filling to a predetermined height each of a series of bottles passed through the machine and particularly to that class of such machines in which a siphon, temporarily inserted in each 20 bottle in a supply tank, is used to convey liquid from the tank to the bottles.

The special object of the invention is to provide especially accurate means for maintaining a constant level of liquid in the supply tank of such a mechanism so that successive bottles filled by the mechanism will all ultimately contain the same amount or height of liquid.

The invention consists in means attaining 30 some or all of the foregoing and other objects, which can be easily and cheaply made; which is satisfactory in use and is not readily liable to get out of order.

The single figure of the drawings illustrates a side elevation largely in section of the mechanism of this invention applied in actual practice to the machine of my said original application.

In the specification, the numerals of reference are for convenience of identification substantially identical with those of the original application.

The left hand two-thirds of the figure of the drawing shows the machine of the original application to which the specific mechanism of the present invention may be readily applied. In general terms, this machine includes a liquid tank 10 carried by a table 12, rotatable on a vertical axle 14, mounted on a stationary frame 16. This shaft or axle 14, and consequently the table, is rotated through the agency of gearing

18-20 and shaft 22 by power mechanism not entering into this invention and not shown. This same shaft drives a longitudinally disposed belt 26, carried by a plurality of pulleys 28, to transport a series of bottles 36 across the front of the machine to a point where they are taken by mechanism not entering into this invention and therefore not shown, and placed upon the table 12 in the notches of a toothed wheel 42 surrounding the tank 10. Above the table and tank described are a series of siphon tubes 70-72 manipulatable by mechanism not entering into this invention and therefore not described, between the position shown in the left hand central portion of the figure in which they clear the bottles 36 below them, and the position on the opposite central portion of the figure in which they enter both the bottle and the tank and thus cause liquid 74 in the tank to flow into and fill adjacent cooperating bottles 36. The essential object of the present invention is to provide means for maintaining the leveling of liquid 74 in tank 10 under all conditions of operation of the device, whereby exactly uniform quantities of liquid will be placed in the successive bottles 36, assuming the position shown at 70 the right hand central portion of the figure.

This result is attained in the mechanism of this invention by making the shaft 14 a hollow pipe with its upper end entering tank 10, and its lower end connected to a hose 120 leading to a special level adjusting apparatus shown at the right of the figure.

The right hand end of pipe 120 enters through valve 122 a tank 124 carried in a frame 126 carrying anti-friction rollers 128 which travel vertically in guides 130 in an enclosing stationary frame 132. The frame 126 and tank 124 is vertically adjustable in frame 132 by a screw 134 rigidly attached to frame 126 and cooperating wheel 136 bearing on the top of frame 132.

Frame 126 carries a liquid pipe 140, having a downturned end 142 entering tank 124, said pipe being continuously supplied with liquid through a pipe leading to a source not shown. On the lower end of pipe portion 142 is a conventional valve 144 and float 146, shown closed in the figure which shuts off liquid from pipe 140 from entering

tank 124 whenever the liquid 74 in tank 124 causes float 146 to reach the shown position on pipe end 142 and causes liquid to flow from said pipe end into the tank whenever the liquid in the tank is so positioned that the float moves downward from the position shown.

As the liquid 74 in the two tanks is in intercommunication through pipe 120, it is obvious that the operator can by operating wheel 136 to bodily raise or lower tank 124 and its level control float mechanism to change the level of liquid in tank 10 without raising its cover 150 and without getting in the way of any of its siphons. By the use of this apparatus, the level of liquid 74 in tank 10 can be adjusted to small fractions of an inch, an important requirement in bottle filling.

Having thus described my invention,

what I claim as new and desire to secure by Letters Patent is:

1. In a bottle filling machine, a vertically immovable tank from which liquid is adapted to be siphoned into bottles an elevatable and depressible tank from which liquid is supplied to said first mentioned tank, and means to maintain liquid at a constant level in said second tank.

2. In a bottle filling machine, a tank from which liquid is adapted to be siphoned into bottles, and means for supplying liquid to said tank including a second tank that is vertically adjustable and that is equipped with a float controlled valve for maintaining a constant level of liquid therein.

In witness whereof, I have hereunto subscribed my name:

ARTHUR I. RISSEK.
